UNITED STATES PATENT OFFICE.

GEORGE L. COWAN, OF EAST RYEGATE, VERMONT, ASSIGNOR TO HOLYOKE MACHINE COMPANY, OF HOLYOKE, MASSACHUSETTS, A CORPORATION OF MASSACHUSETTS.

PISTON.

1,255,081.

Specification of Letters Patent. Patented Jan. 29, 1918.

Application filed April 28, 1916. Serial No. 94,111.

To all whom it may concern:

Be it known that I, GEORGE L. COWAN, a citizen of the United States of America, residing at East Ryegate, in the county of 5 Caledonia and State of Vermont, have invented certain new and useful Improvements in Pistons, of which the following is a specification.

This invention relates to improvements in 10 pistons that are designed to be used in pulp grinding machines, although I do not limit myself to the pulp grinding art.

An object of the invention is to provide a piston which will automatically expand 15 or move the ring of packing material outward against the inner surface of the cylinder in which the piston reciprocates. Broadly, the invention comprises a piston formed with spaced plates or heads, each of 20 the heads having inwardly opening valves to permit the entrance of water, or other fluid, under pressure, to the interior space between the plates, a rim composed of arc-shaped members adapted to move radially outwardly against the packing material, and means for permitting the fluid, under pressure, to gain access to the chamber between the plates in which the arc-shaped members are located, whereby these members, as they 25 move outward, will, under pressure, in turn, compress the packing material against the inner walls of the cylinder for forming a fluid tight joint between the packing and the walls of the cylinder. Means is also 30 provided for guiding the arc-shaped members and retaining the same in place during 35 their radial movements.

Referring to the drawings:

Figure 1 is a general assembly view illustrating the application of the invention to 40 a pulp grinding machine, the upper and lower plates of the piston being shown in section to illustrate the interior arrangement of the parts;

Fig. 2 is a plan view of the interior of 45 the piston with one of the cover plates removed showing the circular-shaped rib integral with the other plate with the openings therethrough; the arc-shaped members 50 for forcing the ring of packing material outward and having stems attached thereto which extends through the openings in the rib, also illustrating one of the inwardly opening valves within the circular rib;

Fig. 3 is a detail view of a portion of

one of the plates or heads of the piston, and showing on an enlarged scale, the inwardly opening inlet valve to permit fluid under pressure to gain access to the interior of the piston, the valve being illustrated in its open 60 position;

Fig. 4 is a transverse sectional view taken on a vertical plane on the broken line 4-4 of Fig. 2, showing the integral hub and rib, the inwardly opening valve in one plate 65 and one of the arc-shaped members with its stem passing through the rib and the spring on the stem between the arc-shaped member and the rib for normally retaining this member in an outward position, and, 70 the packing material in section.

Referring to the drawings in detail: The cylinder in which the piston operates is indicated at 1, the chamber in which the blocks of wood are placed is indicated at 2, and the follower at 3. The piston that is attached to the piston rod 4 includes two plates or heads 5 and 6. Plate 5 is formed with an integral circular rib 7 and an integral hub 8 for attaching the piston rod 4 80 to the piston by inserting the same in the opening 9 as illustrated in Fig. 1. The rib 7 is formed with radially arranged ports or openings 10 and other openings 11, the openings 10 are for the purpose of allowing 85 fluid, under pressure, to pass therethrough, as will be explained in the operation of the piston. The rib 7, it will be observed is only attached to the plate at one edge. 12 designates a plurality of arc-shaped members 90 that are loosely mounted on the inner face of the plate 5, as shown in Fig. 4. Secured to the arc-shaped members are rods 13 which extend inwardly and pass through the openings 11 and mounted on the rods 95 13 are springs 14, that are normally under compression for forcing the arc-shaped members outward against the ring of packing material 15 that extends around the outer surface of the arc-shaped members 12. 100

The plates 5 and 6 are provided with valves 16 and 17 which open inwardly into the space between the plates. These valves are secured in place by means of the bolts 18 that are threaded into the plates 5 and 6 105 and, between the head of the bolts and the valves is placed a compression spring 19 for the purpose of normally holding the valves closed. The plate or head 6 is secured to the plate 5, as stated above, by means of the 110

piston rod 4. The vertical height of the integral rib 7 and hub 8 is such that when the plate or cover 6 is secured in place and rests on the circular rib 7 and the hub 8, the arc-shaped members 12 will have free radial movements between the plates.

In the operation of the valve, considering the piston at the end of its travel or upper position, as shown in Fig. 1, when water, or other fluid under pressure, flows through the port 20 to the chamber 21, the valve 17 in the head 6 will open inwardly allowing the fluid under pressure to pass through the openings 22 and into the chamber or space 23 within the annular rib 7. From this chamber it flows through the ports 10 into the annular space occupied by the arc-shaped members 12. These members will be forced radially outward by the fluid under pressure and against the packing material. This pressure continues until the piston reaches the lower end of its travel and as it is driven backward by the fluid under pressure through the port 24 the valve 16 will then open permitting the fluid under pressure to pass through the openings 22 and ports 10 into the space occupied by the arc-shaped members 12 as before and maintaining the ring of packing material 15 in an outward position tightly against the inner walls of the cylinder 1. It will thus be seen that there is a continuous pressure at all times exerted by the fluid on the arc-shaped members 12 to maintain the packing material tight against the inner surface of the cylinder 1. This construction of valve automatically takes care of and avoids the necessity of repacking the piston when it shows signs of leakage. It also permits the piston to be used until the packing material is entirely worn away. In case of

repairs, or other changes, it is only necessary to remove the plate 6 in order to insert a new piece of packing material or make other repairs. Any suitable valve mechanism may, of course, be employed to control the flow of fluid under pressure through the ports 20 and 24. A slide valve construction is shown at 25 although of course a rotary valve may be used.

What I claim is:

A piston for the purpose described, including separable plates or heads spaced from each other, each plate having an inwardly opening valve, said valves being retained in a guided position by means of bolts located between the heads and secured to the separable plates, a compression spring between the head of each of the bolts and the valves to maintain the same closed, one of the heads having a hub for attaching the piston rod thereto and an annular ring or rib of the same height as the hub and having ports therethrough to permit fluid under pressure to pass therethrough and other openings for guiding arc-shaped expansion members toward and away from the packing material, said inwardly opening valves being located within the annular ring, said arc-shaped members being located near the outer edge of the plates, whereby as the piston reciprocates fluid under pressure will pass to the interior of the piston and through the ports in the rib, for the purpose of moving the arc-shaped expansion members against the packing material, one of the heads resting on the hub and ring for spacing the plates yet permitting the arc-shaped expansion members and packing material to have free movement between the heads.

GEORGE L. COWAN.
